US00D799605S

(12) **United States Design Patent** (10) Patent No.: **US D799,605 S**
(45) Date of Patent: **** Oct. 10, 2017**

(54) **BLOCK FOR BUILDING GAME**

(71) Applicant: **Fontaine Fabien**, Hong Kong (CN)

(72) Inventor: **Fontaine Fabien**, Hong Kong (CN)

(73) Assignee: **Fontaine Fabien**, Hong Kong (CN)

(**) Term: **15 Years**

(21) Appl. No.: **35/501,380**

(22) Filed: **Jul. 20, 2016**

(80) **Hague Agreement Data**

Int. Filing Date: **Jul. 20, 2016**

Int. Reg. No.: **DM/091918**

Int. Reg. Date: **Jul. 20, 2016**

Int. Reg. Pub. Date: **Aug. 5, 2016**

(51) **LOC (10) Cl.** **21-00**

(52) **U.S. Cl.**

USPC **D21/386**

(58) **Field of Classification Search**

USPC D21/385, 386, 390, 488; D11/812;
D19/62
